UNITED STATES PATENT OFFICE.

JAMES R. MIMS, OF LURAY, VIRGINIA.

HOLDER FOR CEMENT-FORMS.

1,149,076.

Specification of Letters Patent. Patented Aug. 3, 1915.

Application filed January 27, 1914. Serial No. 314,300.

To all whom it may concern:

Be it known that I, JAMES R. MIMS, a citizen of the United States, residing at Luray, in the county of Page, State of Virginia, have invented certain new and useful Improvements in Holders for Cement-Forms; and I do hereby declare the following to be a full, clear, and exact description of the invention, such as will enable others skilled in the art to which it appertains to make and use the same.

The present invention is directed to improvements in holders for cement forms, and has for its object to so construct a holder of this nature that the same can be adjusted for forming columns of various sizes.

A further object of the invention is to provide a holder so constructed that the same can be employed for forming octagonal columns as well as square columns.

A still further object of the invention is to so construct a holder of this nature that the bars thereof can be easily and quickly adjusted.

With these and other objects in view, this invention resides in the novel features of construction, formation, combination and arrangement of parts to be hereinafter more fully described, claimed and illustrated in the accompanying drawing, in which:—

Figure 1 is a perspective view of the holder showing the same in position upon a square form. Fig. 2 is a sectional view on line 2—2 of Fig. 1. Fig. 3 is a top plan view of the holder when used in forming octagonal forms. Fig. 4 is a sectional view on line 4—4 of Fig. 3.

The holder comprises bars 1 and 2, the ends of which being adapted to overlap so as to form, in effect, a square frame for engaging the outer surfaces of the form board 3. The bars 1 and 2 each have one of their ends provided with notches 4, said notches being formed upon the outer edges of the respective bars. The other ends of the bars 1 and 2 are provided with a series of aligned perforations 5 which are designed to be arranged in registered relation for receiving the bolts 6, said bolts being slotted, as at 7 for pivotally receiving the plate 8, said plate being disposed in the slot when the bolt is passed through the registered perforation, but will readily swing from engagement with the slot so that the bolt will be prevented from be-

coming accidentally disengaged from the 55 perforation.

Lock plates 9 are provided, and are preferably oval in shape, said plates being provided with longitudinal slots 10, one of which being disposed above the plane of the other so that the notched ends of the bars 1 and 2 may engage in the slots when disposed in overlapping relation.

When the lock plates 9 are engaged with the notched ends of the bars it is obvious that said bars will be prevented from sliding from engagement with each other owing to the fact that the bases of the slots 10 engage certain of the notches 4. The bolts 6 retain the perforated ends of the bars in their proper positions so that when the holder is in place upon the form it is obvious that the boards 3 thereof cannot move outwardly.

When the holder is employed for molding octagonal columns, as illustrated in Fig. 3 of the drawing, strips 11 are provided for each corner of the clamp, said strips consisting of adjustably connected sections 12, the outer ends of which being with slots 13 to 80 engage the adjacent edges of the bars 1 and 2. By adjustably connecting the sections of the strips 11 it is obvious that the same may be adjusted to compensate for the adjustment of the bars when the clamp is adjusted 85 for various sizes of columns. It is to be understood that in using this form of device the strips 1 and 2 engage four of the faces of the octagonal form, while the strips 11 engage the other four faces of the said form. 90 These strips 11 are slidably connected with the strips 1 and 2 so that as the ends of the said strips are spread for the application of the holding plate 9, the said strips 11 will slide thereon. 95

From the foregoing description it will be seen that a holder has been provided which is extremely simple in construction, durable, efficient in operation and one which can be manufactured at a very small cost. 100

What is claimed is:—

1. A holder of the class described comprising a plurality of bars, the ends of which are disposed in overlapping relation, certain of the ends being pivoted together, the other ends of said bars being provided with notches, lock plates having longitudinal slots formed theran for engaging the bars so that

the notches thereof engage the bases of said slots.

2. A holder for concrete forms comprising a rectangular frame, the said frame being composed of strips of metal, the strips at two diagonally opposite corners being pivoted together and at the other opposite corners being overlapped and having diverging ends and a plurality of notches therein, and plates removably mounted be-

tween said diverging ends of the strips and having slots therein arranged to engage the notches in the said ends.

In testimony whereof, I affix my signature, in presence of two witnesses.

JAMES R. MIMS.
